FIRE EXTINGUISHER

Ernest E. Seaberg, Brooklyn, N. Y., assignor to
 Carnoy Products Corporation, Elmsford, N. Y.,
 a corporation of New York

Application December 3, 1948, Serial No. 63,260

4 Claims. (Cl. 169—31)

1

The present invention relates to a novel and improved gas-propelled fire extinguisher.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a vertical section showing a typical and preferred embodiment of the invention;

Figure 2 is a fragmentary side elevation and Figure 3 is a top plan view of the embodiment of Figure 1;

Figure 4 is a detailed sectional view taken on the line 4—4 of Figure 1;

Figure 5 is a bottom plan view of the parts shown in Figure 4; and

Figure 6 is a detailed front elevation of the nozzle shown in Figure 1.

The present invention has for its objects the provision of a highly efficient, compact, simple and relatively inexpensive gas-propelled dry-powder fire extinguisher. A further object is the provision of a novel and improved fire extinguisher which will extinguish large fires with a smaller amount of powder and gas than has heretofore been generally possible. Still another object is the provision of an extinguisher which is effective at unusually long ranges. The invention further provides a gas-propelled, dry-powder extinguisher which can be refilled with a minimum of labor and which can be sealed with certainty.

As illustratively shown in the accompanying drawings the extinguisher of the present invention comprises a gas bottle to contain propellant gas under high pressure, an exterior bottle into which the gas is released and which is filled with powder to be propelled by the gas through a nozzle controlled by a hand valve. Manually opened valve means are provided for releasing the gas from the high pressure bottle, and special sealing means are provided for mounting the inner bottle and its valve within the outer powder-filling bottle.

2

As shown, the outer bottle 10 comprises a generally cylindrical steel container having dome-like ends which are interiorly apertured and threaded to receive the nozzle portion, and the flange of an interior gas bottle.

At one end, 12, the bottle 10 is thickened and interiorly threaded to receive the nozzle and discharge valve assembly. This comprises a strong metal neck 14 having a gradually constricted and curved interior passage 16 which leads to a valve and discharge nozzle. The neck is exteriorly threaded to fit tightly by threads 18 in the bottle and is sealed thereto by gasket 20. The valve means comprises a cylindrical plug 22 slidable in a cylindrical bore formed in the neck casting and urged to closing position by means of a coil spring 24 compressed between an end of the plug 22 and a cap 26 threaded into the bore. Plug 22 is formed with an annular groove 28 which may coincide with the passage 16 so as to provide for discharge through the valve. Plug 22 is sealed in its bore by means of the small O-rings which are seated in annular grooves at either side of the groove 28.

Groove 28 and passage 16 communicate with the nozzle which comprises a short cylindrical tube 30 coaxial with passage 16 and of a slightly larger interior diameter than passage 16, as shown in Figures 1 and 6. When plug 22 is moved to fully open position, the annular groove 28 as intersected by the passage 16 forms two rounded openings at the sides of the passage 16 thereby providing for two streams of propelled powder, which streams are directed towards each other, merge and are deflected by the interior walls of the tube 30 so as to form a gradually increasing cone of powder which is propelled to a considerable distance, often as far as thirty or forty feet.

For opening and closing the discharge valve by axial movement of plug 22, a yoke 33 is fastened to the lower end of plug 22 and is formed with slots 35 which receive the rounded ends of a loop shaped lever 37 pivoted at 38 on a pin 45 extending through the neck casting 14. Stops 39 formed integrally with casting 14 limit movement of the lever 37 by spring 24. When lever 37 is manually depressed, the valve plug 22 is moved to open or discharge position.

The interior or high pressure gas bottle comprises a standard small steel bottle 40 for containing high pressure carbon dioxide or nitrogen under a pressure of 1000 to 2500 pounds per square inch pressure. Bottle 40 is threaded at one end to receive a valve 42 of standard con-

struction which is opened by relative rotation of the valve stem by means of the winged finger disc 44. Disc 44 is mounted on the valve spindle 46 with a small amount of play and may be "sealed" to the valve body by means of pin 48 which projects through an aperture in the disc and into a hole 50 in the flange 51 fixed to the valve body 42.

When pin 48 is in place it is usually "sealed" by means of a wire seal 52 passed through the loop of pin 48 and apertures in lugs 54 on the flange. When the extinguisher is to be used, the pin 48 may be pulled by breaking the sealing wire 52 thereby allowing the finger disc 44 to be turned to open the valve, causing the high pressure gas to be discharged into bottle 10 and readying the extinguisher for use under control of the nozzle valve actuating lever 37.

Figure 4 shows the details of the illustrative valve assembly. As embodied the valve body 42 is threaded into the neck of bottle 40. Valve body 42 is formed with a discharge passage 55 leading from the bottle 40 to the side of the body 42 and including a valve seat 56 to be closed by the valve gasket 58 carried by threaded member 60 which is keyed to the valve spindle 46 so as to be moved to open and closed position by disc 44.

Bottle 40 is securely mounted in the bottle 10 by means of flange 51 which is stepped to provide a circular lip 61 which is received within the smooth short cylindrical bore 62 formed by the adapter 63 screwed into the apertured bottom of bottle 10. Lip 60 seats against gasket 64 to form a gas-tight closure and is held thereagainst by means of the hand wheel 66 and its retaining collar 68, threaded to the adapter 63 and formed so as to press the flange 51 tightly against gasket 64, thus also firmly holding the interior bottle against relative movement.

In reloading the extinguisher, it is inverted, the hand wheel 66 is removed, freeing the interior bottle 40. The bottle 10 is substantially filled with powder, a charged gas bottle 40 with its attached valve is inserted into the powder and then the hand wheel 66 is replaced and tightened. Only the bottle 40 and its valve assembly need be shipped back to the factory for recharging and the extinguisher as a whole can be reloaded without special tools or great trouble.

The invention in its broader aspects is not limited to the specific mechanisms shown and described but departures may be made therefrom within the scope of the accompanying claims without departing from the principles of the invention and without sacrificing its chief advantages.

What is claimed is:

1. In a gas propelled dry powder fire extin-

guisher the combination of a large bottle to be filled with the dry powder and having a wide mouth opening at one end thereof, said wide mouth opening provided with an internally recessed seat and a threaded exterior surface, a flanged valve member seated within the recessed seat of said opening by means of said flange, the inlet end of said valve member rigidly secured to the discharge end of a gas bottle positioned within said large bottle, the discharge opening of said valve member being completely within said large bottle, and a threaded ring screwed on to the mouth of said large bottle and securely clamping the flange to its seat and holding the gas bottle in position.

2. An extinguisher according to claim 1 in which a valved nozzle is positioned to said large powder containing bottle at the end opposite to the wide mouth opening of said large bottle.

3. In a dry powder fire extinguisher the combination of a large bottle to be filled with dry powder and having a wide mouth opening at one end thereof and a valved discharging outlet at the opposite end thereof through which the powder is to be expelled under pressure, a smaller high pressure gas bottle removable through the mouth opening of said large bottle, and means for supporting the gas bottle within the first bottle comprising a valve member attached to the gas bottle at the inlet end of said valve member and controlling the flow of gas therefrom into said large bottle, the discharge opening of said valve member being completely within said large bottle, said valve having a disc-like flange and an external control member, the mouth opening of said large bottle having a recessed seat to receive said flange of said valve member, and means for tightly holding said flange to its seat.

4. An extinguisher according to claim 3 in which the control member has limited rotation with respect to its valve and the control member and flange are apertured to receive a sealing pin.
